UNITED STATES PATENT OFFICE.

ALEXANDER JACOBI, OF ST. CLAIR, MICHIGAN.

BURGLAR-ALARM.

SPECIFICATION forming part of Letters Patent No. 320,660, dated June 23, 1885.

Application filed April 15, 1885. (No model.)

To all whom it may concern:

- Be it known that I, ALEXANDER JACOBI, of St. Clair, in the county of St. Clair and State of Michigan, have invented new and useful Improvements in Burglar-Alarms; and I do hereby declare that the following is a full, clear, and exact description thereof, reference being had to the accompanying drawings, which form a part of this specification.
10. This invention relates to a new and useful improvement in burglar-alarms of that kind where the ringing of the alarm-bell is produced by mechanical means.
- The object of my invention is to improve 15 the device described in a patent granted to me March 24, 1885, No. 314,450; and the improvement consists in the arrangement of certain devices, hereinafter described, for connecting doors or windows with the alarm-cord.
20. Figure 1 is a perspective view of a door to which my device for operating the alarm is applied. Fig. 2 shows a part of Fig. 1 on a larger scale. Fig. 3 is a detached perspective view of the weight-supporting staple.
25. Fig. 4 is a horizontal cross-section of a door opening toward the outside, and to which a modified form of my device is applied. Fig. 5 shows my device as applied to a window.
- In the accompanying drawings, which form 30 a part of this specification, A is the burglar-alarm operated by clock-work in the usual manner, and provided with the alarm-bell B and hammer C. D is a vertical sliding detent, which, when engaging into the eye E on the hammer-arm, locks the hammer in position, and which, when lifted up by a pull on the alarm-cord F, liberates the hammer and allows it to ring the bell.
- The parts just described are substantially 35 the same shown in my above-mentioned patent.
- To protect a door with a burglar-alarm of this kind, I have arranged the following contrivance: G is a weight attached to a branch cord, H, which runs up vertically, then passes over a pulley, I, or through a staple, and, after running a little distance in a horizontal direction, connects with the main alarm-cord F. K is a staple driven into the door-casing, 45 so as to form a support on which the weight G may stand. I preferably cover the staple
- K with a little tin plate, L, suitably secured thereto, as shown in Fig. 3, so as to form a convenient platform for the weight. M is a little sliding rod, secured to the door in such 55 position that it may be projected behind the weight. With the parts thus arranged it will be seen that on opening the door the rod M will push the weight G off the platform. Its gravity in falling will then pull the alarm-cord, 60 lifting the detent D and setting the alarm to ring.
- It will be seen that by an arrangement of this kind the alarm-cords F H can be arranged with a considerable slack, and no failure or false alarm can occur, owing to the contraction or expansion of the alarm-cords, providing the weight G is put sufficiently high above the floor to give it a considerable fall to take up the slack of the cords. As the operation of the weight is almost instantaneous, 65 as soon as the door is opened the least bit, no amount of dexterity or knowledge on the part of the intruder can defeat its object.
- To disconnect the door from the alarm-cord 70 the weight G is taken off its platform and hung on a nail or hook, N, conveniently secured near by, and the arm M is retracted out of the way.
- For an outside door I arrange the weight 75 and platform on the inside of the door-jamb, as shown in Fig. 4, and provide the arm M with a little return-bend, O, which, when the door is opened, will pull the weight off the platform.
- The device, if desired, may be equally well 80 applied to windows, in which case the parts are suitably arranged to operate by the raising of the lower sash, as shown in Fig. 5, in which case the pin m is attached to the window-sash, and is bent as shown. When the window is raised, this inclined portion, acting as a wedge, forces the weight off its platform by reason of its engagement with the pin m, with which the weight is provided.
- It will be seen that my contrivance permits 85 of connecting all the doors and windows of a dwelling to one alarm.
- What I claim as my invention is—
1. In a burglar-alarm, the combination of 90 a weight-supporting platform arranged in proximity to a door or window, a weight at-

tached to the operating-cord and supported by said platform, and a rod arranged in the path of the weight, whereby the opening of the door or window moves the weight from its 5 platform, substantially as and for the purpose specified.

2. In a burglar-alarm operating as described, the combination of the weight G, staple K,

sliding rod M, and alarm-cords H I, all combined and operating as described.

Detroit, Michigan, April 3, 1885.

ALEXANDER JACOBI.

In presence of—

H. S. SPRAGUE,
E. J. SCULLY.
